(57) **CLAIM**

The ornamental design for an “LED light bulb for a light strip”, as shown and described.

DESCRIPTION

FIG. 1 is a perspective view of a LED light bulb for a light strip, showing my new design;

FIG. 2 is a front elevational view thereof, the right side, left side, and rear elevation views being mirror images thereof;

FIG. 3 top plan view thereof; and,

FIG. 4 is a bottom plan view thereof.
